UNITED STATES PATENT OFFICE.

EDWARD J. VON PEIN, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CASH-REGISTER

1,244,005.

Specification of Letters Patent. Patented Oct. 23, 1917.

Original application filed November 15, 1913, Serial No. 801,293. Patent No. 1,198,492, dated September 19, 1916. Divided and this application filed March 23, 1916. Serial No. 86,097.

To all whom it may concern:

Be it known that I, EDWARD J. VON PEIN, a citizen of the United States, residing at Dayton, in the county of Montgomery and 5 State of Ohio, have invented certain new and useful Improvements in Cash-Registers, of which I declare the following to be a full, clear, and exact description.

This invention relates to perforating 10 mechanism for strips of material.

This application constitutes a division of application Serial No. 801,293, filed November 15, 1913 and a reference may be had to said application for a specific embodiment 15 of this invention.

In previous constructions the perforator is usually carried by a rotatable element having an invariable movement and the perforator teeth are so arranged that all are 20 brought into play at the same instant. This causes the machine to run hard at that particular point of the operation. One object of the present invention is to provide a perforator so arranged that the teeth, while 25 they are carried by an invariably moved rotatable element and perforate in a straight line at right angles to the length of the strip of material, are not brought into play simultaneously, but one after the other, 30 thereby distributing the perforating operation over a greater part of the operation of the machine and making the machine run more easily.

Another object of the invention is to provide improved means for holding the paper against or opposing it to the teeth of the 35 perforator.

In previous constructions a roller of rubber or similar yielding material was used, 40 into which the teeth of the perforator sank after they passed through the paper. Such rollers are necessarily short lived and therefore unsatisfactory, a condition which the applicant remedies by using an improved 45 roller made of steel or other durable material and arranged to accomplish the same result as the rubber roller.

With these and incidental objects in view, 50 the invention consists of certain novel features of construction and combination of parts, the essential elements of which are set forth in appended claims, and a pre-

ferred form of embodiment of which is hereinafter described.

With reference to the drawings which accompany and form part of the specification:—

Figure 1 is rear view of the perforating devices and some of their driving connections.

Fig. 2 is a top view of the perforating devices.

Fig. 3 is a detail of the gearing and connections of the perforator rollers.

Fig. 4 is a detail of a cam for shifting the 65 perforator rollers.

Fig. 5 is a cross section of the rollers.

The perforator mechanism comprises the roller 82, carrying the perforator blade 101 and a roller 81 composed of steel or similar 70 material and having annular grooves 127, corresponding to the teeth in the perforator. The shaft 80, upon which the roller 81 is loosely mounted, has secured thereto a gear 79 and a disk 129. The gear 79 may be connected in any desired way to a part of the machine of which the present invention is made an element. Fastened to the roller 81 is a disk 133 and a gear 131. In order to allow the roller 81 to move laterally on its 80 shaft, the roller 81 is driven through studs 135, secured to the gear 131, and projecting into holes in the disk 129. The perforator roll 82, loosely mounted on the shaft 95, has rigidly secured to it the disk 134, and the 85 gear 132. The gear 131 meshes with the gear 132 and the disk 133 extends into the recess between the disk 134 and the gear 132, so that any lateral movement of one roller will be imparted to the other and the 90 teeth of the perforator and the grooves of the roller 81 will always be held in alignment. Both the roller 82 and the roller 81 are set at an angle to the length of the strip of material 83 to be perforated, as shown in 95 Fig. 1, but parallel one to the other with the strip 83 passing between them. The roller 82 is cut away, as shown in Fig. 5, and the perforator blade 101 is attached to one of the sides of said cut. The cut is so made 100 that the perforator blade when assembled in position is substantially spiral to the axis of the roller 82, but owing to the angle at which the roller is set, the line of the teeth

is at right angles to the edges of the strip 83. The line of the teeth also conforms to the curvature of the roll 82 and when the rollers are rotated, the teeth at the end 138, are first brought into engagement with the paper and the other teeth are carried in successively until the ones at the end 139 have performed their work. By this arrangement of the blade, the teeth are not carried into contact with the strip simultaneously, but at the same time the line of perforation is at right angles to the length of the strip.

However, owing to the angular position in the printer of the perforator rollers, the path of rotation of the teeth is not parallel to the length of the strip and the tendency would be, therefore, to pull the strip to one side while the perforator teeth are in engagement with it. To offset this, there is attached to the outer end of the roller 82, a cam 141 into the slot of which there extends an antifriction roller 142 carried by a bracket 143 secured to the frame of the device. At the instant that the teeth 138 of the perforator engage the strip the point 144, Fig. 4, of the cam slot strikes the roller 142 and the rollers 81 and 82 through the connection established by the disk 133 are both shifted laterally on their shafts until the point 145 of the cam slot passes the roller, at which time the last tooth at the end 139 of the perforator passes out of engagement with the strip. The surface 146 of the cam then shifts the rollers back to their normal position, in which position they remain during the rest of the rotation.

The portion 144 to 145 of the cam slot is so graduated that during the time the teeth of the perforator are working their line of travel is in a plane parallel to the edges of the strip instead of being as it is normally at right angles to the inclined shaft 95. This overcomes the tendency to pull the strip to one side and causes it to move continuously in the direction of its length, even while the perforator teeth are in engagement with it.

The actuation of the rollers may be intermittent or constant as desired and the strip of material may be moved any desired distance between perforating operations without departing from the present invention.

While the form of mechanism herein shown and described is admirably adapted to fulfil the objects primarily stated, it is to be understood that it is not intended to confine the invention to the one form of embodiment herein shown and described, as it is susceptible of embodiment in various forms, all coming within the scope of the claims which follow.

What is claimed is:—

1. In a machine of the class described, the combination with a rotatable element carrying teeth for perforating a strip of material,

said teeth being arranged substantially spiral to the axis of the rotatable element and normally rotating in planes oblique to the length of the strip, of means for shifting the rotatable element to cause said teeth to move in planes parallel to the length of the strip during a part of each rotation of their carrying element. 70

2. In a machine of the class described, the combination with a rotatable element comprising teeth for perforating a strip of material, said teeth being arranged substantially spiral to the axis of the rotatable element and rotating mainly in planes oblique to the length of the strip, of means comprising a cam for shifting the rotatable element to cause said teeth to move in planes parallel to the length of the strip during a part of each rotation of their carrying element. 75

3. In a machine of the class described, the combination with a rotatable element carrying teeth for perforating a strip of material, said teeth being arranged substantially spiral to the axis of the rotatable element 80 and rotating mainly in planes oblique to the length of the strip, a second rotatable element having annular grooves to coöperate with the perforator teeth, and means comprising a cam for shifting both of said 85 rotatable elements to cause the perforator teeth to move in planes parallel to the length of the strip while said teeth are coöperating with the second rotatable element. 90

4. In a machine of the class described, the combination with a rotatable element carrying teeth for perforating a strip of material, said teeth being arranged substantially spiral to the axis of the roll, a second rotatable element having annular grooves coöperating with the perforator teeth, the axes of the rotatable elements being parallel one to the other and oblique to the length of the strip, and means comprising a cam for shifting said rotatable elements to cause the perforator teeth to feed the strip in the direction of its length while said teeth and the second rotatable element are in coöperating relation. 100

5. In a machine of the class described, the combination with a rotatable element, of perforator teeth carried by said rotatable element and arranged substantially spiral to the axis of said element, and a second rotatable element having annular grooves coöperating with the perforator teeth. 115

6. In a machine of the class described, the combination with a rotatable element, of a set of perforator teeth carried thereby, and a second rotatable element having annular 125 grooves coöperating with said perforator teeth.

7. A strip perforating device comprising a rotatable element having its axis parallel to the surface of and oblique to the length of 130

the strip, a series of perforator teeth carried by said element and so disposed with reference to the axis of the element that they are brought into play one after the other by 5 rotations of the element but perforate in a straight line at right angles to the length of the strip, a movable element having depressions coöperating with the perforator teeth, and means for driving said rotatable 10 element.

8. A strip perforating device comprising a rotatable element having its axis parallel to the surface of and oblique to the length of the strip, a series of perforator teeth carried by said element and so disposed with reference to the axis of the element that they are brought into play one after the other by rotations of the element but perforate the strip in a straight line at right 15 angles to the length of the strip, and means for driving said rotatable element, means for opposing the strip to the teeth of the perforator, means for shifting the rotatable element laterally during rotation of said element, and connections whereby the shifting movement of said element is transmitted to 20 the opposing means.

9. A strip perforating device comprising a rotatable element having its axis parallel to the surface of and oblique to the length of the strip, a series of perforator teeth carried by said element and so disposed with reference to the axis of the element that they are brought into play one after the other by rotations of the element but perforate in a straight line at right angles to the length of the strip, an element having 25 grooves coöperating with the perforator

teeth, and means for moving the rotatable element and the grooved element laterally 40 during rotations of the former.

10. In a machine of the class described, the combination with a rotatable element, of a series of strip perforating teeth carried by said element, the teeth being arranged 45 substantially spiral to the axis of the carrying element and the element so inclined that its axis is oblique to the length of the strip, a second rotatable element having annular grooves coöperating with the perforating 50 teeth and inclined to bring its axis parallel to the axis of the tooth carrying element, and means for driving the two rotatable elements.

11. A device for perforating a moving ticket strip comprising a rotatable element having its axis diagonal to the line of travel of the ticket strip, a perforating blade carried by said rotatable element, means for opposing the ticket strip to the perforating 55 blade, and means for shifting the rotatable element laterally during the time said blade is acting upon the strip.

12. A device for perforating a moving ticket strip comprising a roller having its 60 axis diagonal to the line of travel of the ticket strip, a perforating blade carried by said roller, means for opposing the ticket strip to the perforating blade, and a cam 65 constructed to gradually move the rotatable member endwise while said blade is acting upon the strip and then return the member to its original position.

In testimony whereof I affix my signature.

EDWARD J. VON PEIN.
